UNITED STATES PATENT OFFICE.

GEORGE E. PELLISSIER, OF JERSEY CITY, NEW JERSEY, ASSIGNOR TO LOUIS D. PELLISSIER, OF HOLYOKE, MASSACHUSETTS.

RAIL-GRINDER.

1,034,029.

Specification of Letters Patent. Patented July 30, 1912.

Application filed January 19, 1911, Serial No. 603,526. Renewed June 7, 1912. Serial No. 702,363.

To all whom it may concern:

Be it known that I, GEORGE E. PELLISIER, citizen of the United States, and resident of Jersey City, in the county of Hudson and State of New Jersey, have invented certain new and useful Improvements in Rail-Grinders, of which the following is a specification.

This invention relates to certain improvements in rail grinders and more particularly to that type which embodies a truck carrying a grinding member so mounted that when the truck is moved along the track the grinding member will be moved along the rail forming a portion of the track to remove surface irregularities therein.

The object of the invention specifically claimed in this application is to provide an automatic lowering and raising of the grinding member bodily with the truck frame during the propelling of the truck along the track to accomplish the removal of sharp depressions in the rail, as at so-called "pounded joints," by forming a long shallow depression merging into the straight portions of the rail surface.

Other objects and advantages as specifically claimed in this application will be set forth hereinafter in the following specification, which should be read in connection with the illustrative embodiment of the invention shown in the accompanying drawings in which,—

Figure 1 is a top plan view of a rail grinder constructed in accordance with my invention, a portion thereof being broken away and a portion being shown on the line 1—1 of Fig. 3; Fig. 2 is a vertical longitudinal section on the line 2—2 of Fig. 1; Fig. 3 is a transverse vertical section, the power means for one of the grinding members being removed; Fig. 4 is an enlarged face view of the wheel shown at the left end view of Fig. 2, the axle being adjusted to eccentric position; Fig. 5 is a sectional view of the wheel shown in Fig. 4, and Figs. 6, 7, and 8 are diagrammatic views illustrating different positions assumed by the grinder during the operation of removing a sharp dip or depression in the rail.

In the specific form of my invention here illustrated, I mount the grinding members, which are preferably emery wheels, upon a truck having a main frame 10 formed of

channel iron. Adjacent opposite ends of the frame are bearings for the axles 11 and 12, and upon these axles are pairs of wheels 13 and 14 mounted to travel along the rails forming the track. Extending across the frame intermediate the ends thereof is a cross-rail 15 serving as a support for the grinding members. This cross-rail is illustrated as being rigidly secured in place at a point somewhat nearer the axle 11 than the axle 12, but it is evident that the cross-rail might be secured in place at any point along the length of the frame of the truck and might be so mounted as to facilitate its adjustment from one position to another. Mounted upon this cross-rail or guide are two saddles or slides 16 so constructed as to be retained in engagement with the cross-rail, but being adjustable along the length thereof in a direction transversely of the track. Preferably, these saddles have removable flanges 17 for retaining them in position and by the removal of which the saddles may be taken off the cross-rail. Extending lengthwise of the rail are two screw rods 18 provided with handles 19 at their outer ends and having threaded engagement with projections 20 on the saddles so that by turning the handles the saddles may be drawn along the cross-rail to any position desired.

Mounted upon each saddle or horizontally movable slide 16 is a bracket or vertically movable slide 21. These brackets may be retained in engagement with the saddles in any suitable manner, but preferably by means of a dove-tailed guide and guideway as shown in the upper portion of Fig. 1. Vertically disposed within each bracket is a screw rod 22 having a handle 23 at its upper end and having threaded engagement with the projection 24 on the saddle so that by turning the handle 23 the bracket may be raised or lowered. This raising or lowering of the bracket is independent and unaffected by the lateral movement of the saddle. Each bracket has depending arms carrying a shaft 25 to one end of which is secured a grinding member 26 which, as hereinbefore stated, is preferably in the form of an emery wheel. This emery wheel is of any shape or contour desired, dependent upon the shape and character of the rail to be ground and the nature of the irregularities to be removed. At the left-hand side of

Fig. 3 I have shown one form of emery wheel for grinding one type of rail and at the right-hand side I have shown a somewhat different wheel for grinding an ordinary T-rail. Each bracket 21 carries a motor 27, here shown as an electric motor, which preferably is detachably and adjustably connected to the bracket by suitable fastening means, such as the bolts 27' engaging the bracket through elongated slots 27" therein. From said motor power is transmitted to the shaft 25 in any suitable manner, as for instance, by a belt 28. By the mechanism above described the emery wheels may be adjusted vertically or laterally to any desired position relatively to the rails to be ground and when in this position the truck or vehicle bearing the grinding members may be moved in engagement with the rails so as to grind the latter in a desired manner.

For propelling the vehicle I preferably provide one of the axles, for instance, the axle 11, with one or more worm wheels 29 adapted to mesh with a worm 30 mounted on a shaft 31 extending upwardly to a point above the platform supported by the main frame. Said shaft preferably extends through a sleeve 32 which is pivotally mounted at 32' beneath the platform. With the shaft extending in the position indicated in Fig. 2 the worm is in engagement with the worm wheel and the vehicle may be slowly advanced by turning the handle 31' at the upper end of the shaft. When it is desired to advance the vehicle at a greater rate of speed with the grinding member out of operation the shaft 31 may be swung about the pivot 32' so that its axis will occupy the position diagrammatically indicated and the worm will be out of mesh with the worm wheel. Any suitable locking device may be employed for holding the shaft in either of its limiting positions. The platform is preferably provided with a slot through which the shaft may move, and pivoted dogs 33 are mounted at the ends of the slots and movable into position within the slot to prevent the swinging movement of the shaft. In certain forms of my improved device I may mount an electric motor on the platform and drive the car at the desired slow rate of speed by this motor, releasably geared to the worm shaft 31, if desired.

In order to grind out sharp depressions or so-called "pounded joints", I preferably so mount the wheels at one end of the main frame that their axle may be brought to an eccentric position. By having the axle eccentric, the frame and therefore the supported emery wheels may be caused to gradually lower and raise during the advancement of the grinder through a predetermined distance dependent upon the circumference of the eccentric wheels. As shown

in Figs. 2, 4 and 5, the wheels 14 are bored to a considerably larger diameter than the axles, and within the bored out hub is placed a bushing 34. This bushing constitutes a mounting for the wheel upon the axle and has the passage therethrough disposed somewhat off center. The bored passage through the wheel is also off center preferably the same amount as is the passage through the bushing 34 off center so that in rotating the bushing in respect to the wheel the axle may be brought to the true center of the wheel or may be brought off center to varying degrees. Suitable means is shown provided for fixing said wheel to said bushing in various positions of relative rotation to adjust the degree of eccentricity between said wheel and its axis. As shown, each bushing has a flange 35 disposed adjacent one surface of the wheel and provided with a plurality of notches 36 about the periphery thereof. A slide 37, having a key projection 37' for engagement with the flange 35 within its said notches, is adjustably connected to the wheel by screws 38 so that when it is moved into engagement with the flange 35 it will lock the wheel and bushing against relative rotation. Access to these adjusting means from the platform of the car may be conveniently had through an opening 39 in said platform which is normally closed by a swinging door 40.

Normally the axle 12 is at the center of the wheel 14 so that the wheels and grinding members move substantially parallel and the emery wheels grind the track smooth and straight. When it is desired to grind out a depression in the track, however, the wheels 14 are brought to an eccentric position, the eccentricity depending upon the depth to which it is desired to grind the rails at the joint.

In Figs. 6, 7 and 8, I have shown the parts somewhat diagrammatically and adjusted for grinding out a depression, the depression and eccentricity adjustment being shown exaggerated to render the disclosure more clear. Starting with the parts in the position shown in Fig. 6 and slowly advancing the grinder, the emery wheel 26 will gradually lower as the grinder advances until the lowest point of the main depression is reached, as shown in Fig. 7, and then will gradually rise, grinding to less and less depth, until finally the elongated and now shallow depression, indicated by dotted lines, merges into the normal surface of the rail, as shown in Fig. 8. After a depression in a rail is ground out in the manner described, the wheels 14 may be readjusted so as to be concentric with their axle and the grinder may then proceed along the track removing such irregularities as may occur.

Having now described one embodiment of

my invention, what I claim as new and desire to secure by Letters Patent of the United States is:

1. A rail grinder comprising a main truck-frame; a rotary grinding member journaled pendant from said frame to engage a rail surface; a motor mounted on said frame; driving connections from said motor to said grinding member; supporting axles mounted at opposite ends of said frame; rail-engageable wheels mounted on said axles, one being an eccentric wheel; means for propelling said grinder along the track; and means for setting and securing said eccentric wheel concentric and in various degrees of eccentricity relatively to its axis, whereby the grinding member and connected parts will be automatically lowered and raised as the grinder is propelled along the track.

2. A rail grinder comprising a main truck-frame; a rotary grinding member journaled pendant from said frame to engage a rail surface; a motor mounted on said frame; driving connections from said motor to said grinding member; supporting axles mounted at opposite ends of said frame; rail-engageable wheels mounted on said axles, one being an eccentric wheel; means for propelling said grinder along the track; said eccentric wheel having an eccentric boring; an eccentric bushing fitting said boring and embracing said axle; and means for fixing said wheel to said bushing in various positions of relative rotation to adjust the degree of eccentricity between said wheel and its axis, whereby the grinding member and connected parts will be automatically lowered and raised as the grinder is propelled along the track.

3. A rail grinder comprising a main truck-frame; a rotary grinding member journaled pendant from said frame to engage a rail surface; a motor mounted on said frame; driving connections from said motor to said grinding member; supporting axles mounted at opposite ends of said frame; rail-engageable wheels mounted on said axles, one being an eccentric wheel; means for propelling said grinder along the track; said eccentric wheel having an eccentric boring; an eccentric bushing fitting said boring and embracing said axle; and means, comprising a notched flange on said bushing and a notch-entering key secured to the wheel, for fixing said wheel to said bushing in various positions of relative rotation to adjust the degree of eccentricity between said wheel and its axis, whereby the grinding member and connected parts will be automatically lowered and raised as the grinder is propelled along the track.

4. A rail grinder comprising a main truck-frame; a rotary grinding member journaled pendant from said frame to engage a rail

surface; a motor mounted on said frame; driving connections from said motor to said grinding member; supporting cross axles journaled to opposite ends of said frame; a pair of spaced rail-engageable wheels mounted on one of said axles; a pair of spaced rail-engageable eccentric wheels movably mounted on the other of said axles; means for propelling said grinder along the track; and means for setting and securing said eccentric wheels concentric and in various degrees of eccentricity relatively to their axes whereby the grinding member and connected parts will be automatically lowered and raised as the grinder is propelled along the track.

5. A rail grinder comprising a main truck-frame; a rotary grinding member journaled pendant from said frame to engage a rail surface; a motor mounted on said frame; driving connections from said motor to said grinding member; supporting cross axles journaled to opposite ends of said frame; a pair of spaced rail-engageable wheels mounted on one of said axles; a pair of spaced rail-engageable eccentric wheels movably mounted on the other of said axles; means for propelling said grinder along the track; each of said eccentric wheels having an eccentric boring; an eccentric bushing fitting said boring and fixed to the axle; and means for fixing said wheel to said bushing in various positions of relative rotation to adjust the degree of eccentricity between said wheel and said axle, whereby the grinding member and connected parts will be automatically lowered and raised as the grinder is propelled along the track.

6. A rail grinder comprising a truck-frame; a plurality of wheels supporting said frame; a grinding member mounted on said frame; means for vertically adjusting the position of said grinding member; and means for slowly advancing said grinder comprising a worm gear mechanically connected to rotate one of said wheels, a worm to mesh with said worm-wheel, a worm-shaft for said worm, means for driving said shaft, a bearing sleeve for said shaft pivoted intermediate the ends of said shaft to said frame, whereby the shaft may be swung to move said worm into and out of mesh with said worm-gear and to move the opposite or driven end of said shaft in the opposite direction, and releasable means for locking said shaft in position to hold said worm in mesh.

7. A rail grinder comprising a truck-frame; a plurality of wheels supporting said frame; a grinding member mounted on said frame; means for vertically adjusting the position of said grinding member; means for horizontally adjusting the position of said grinding member; and means for slowly advancing said grinder comprising a worm gear mechanically connected to rotate one

of said wheels, a worm to mesh with said worm-wheel, a worm-shaft for said worm, means for driving said shaft, a bearing sleeve for said shaft pivoted intermediate the ends of said shaft to said frame, whereby the shaft may be swung to move said worm into and out of mesh with said worm-gear and to move the opposite or driven end of said shaft in the opposite direction, and

releasable means for locking said shaft in 10 position to hold said worm in mesh.

Signed at New York, in the county of New York, and State of New York, this 17th day of January, A. D. 1911.

GEORGE E. PELLISSIER.
